HEAT EXCHANGER

Giovanni Rossi, Milan, Italy

Application May 25, 1954, Serial No. 432,225

Claims priority, application Italy May 25, 1953

2 Claims. (Cl. 257—222)

The present invention relates to a heat exchanger particularly suitable for high pressures and corrosive liquids.

It is an object of the present invention to realize a heat exchanger uniting the following characteristics:

(1) Expanded and/or welded tubes;

(2) Tubes of the end tube plates fully accessible for cleaning out solid materials from vapor sublimation in the conduits or from incrustations due to other causes;

(3) The use of very long tubes in order to have a large exchange surface in a small diameter outer shell;

(4) Tubes working only under tension and requiring therefore a limited thickness which is particularly interesting when high-priced materials have to be used, which generally possess but a limited ability to withstand mechanical stresses;

(5) Possibility of shortening the tubes for re-expansion, they not being bonded by any fixed point (for maintenance, breakage, repair etc.);

(6) Internal tube bunch free to expand;

(7) Simplification on the whole in respect to the known types and consequent lower cost.

The exchanger according to the invention is substantially characterized by the fact that the conduits of the tube bunch through which the inner fluid circulates are fixed by at least one of their ends to a tube plate free in respect to the shell through which circulates the inner fluid, so that the conduits of the tube bunch are stressed under tension by the effect of the internal pressure and free to expand in respect to the shell for the external fluid.

The invention will be described with reference to the annexed schematic drawings given only as an indicative example and in which:

Fig. 1 shows in longitudinal section a first form of realization of the exchanger;

Fig. 2 is a cross section according to line II—II of Fig. 1;

Fig. 3 is a cross section according to line III—III of Fig. 1;

Fig. 4 is a cross section according to line IV—IV of Fig. 1;

Fig. 5 is a detail, sectioned and on a larger scale, of the free tube plate of the exchanger illustrated in Fig. 1;

Fig. 6 is a sectioned detail of the separating diaphragm of the internal fluid chambers;

Fig. 7 shows a sectioned variant of the free tube plate;

Fig. 8 is a cross section of the above;

Fig. 9 is a section of a constructional variant of the free tube plate;

Figs. 10, 11 and 12 show in a longitudinal section three different constructional forms of the exchanger according to the invention.

Referring now to Figs. 1 and 6, A indicates the outer cylindrical shell of the apparatus, in which the external fluid entering from above through fitting 1 circulates and leaves, also from above, from connection 2. Shell A is closed at its ends by removable flanged upper 3, and lower 4, covers. Between upper cover 3 and cylindrical shell A tube plate 5 is closed water tight, and to it are fixed the

2

ends of tubular elements B in which the inner fluid circulates.

The connection between such tubular elements and plate 5 can be effected by expansion and/or welding.

5 The inner fluid reaches chamber 6 comprised between cover 3 and tube plate 5 through connection 7, and leaves the apparatus, after having reached chamber 8 comprised between cover 3 and tube plate 5, through connection 9.

The two chambers 6 and 8 are separated from one another by a water tight plane diaphragm 10 welded to cover 3 and cooperating at its lower border with a diametral groove of tube plate 5 (Fig. 6) and a gasket 11 disposed at the bottom of said groove.

Tubular elements B are connected at their other end to a second tube plate 12, parallel to the first one. Plate 12 carries as many through holes having their axes square with their bases, as tubes B are. The latter have their ends disposed inside said holes and are connected to the plate by expansion. Holes 13 are closed by means of screw caps 14 permitting said tubes to be cleaned. Hydraulic connection between the several conduits B in plate 12 is obtained by means of cross holes 15 closed at the end with screw caps 16.

The inner fluid of chamber 6 travels therefore one half 25 of tubes B and then flows, through conduits 15, into the other half of tubes B, discharging into chamber 8 and therefrom to the outside. By providing the cylindrical shell A with a central diaphragm 17 in line with diaphragm 10 for the shell fluid, movement of the two fluids 30 is obtained in counter-current, improving the transmission of heat. Diaphragm 17 will, of course, have to permit a passage for the outer fluid in correspondence with the lower part of body A.

The lower cover 4 is provided with an opening 18 for bottom discharge.

Conduits B may be differently employed for the passage of the inner fluid by disposing, for instance, more than one diaphragm like 10 in the chamber 6—8 and eventually putting in communication each tube in tube 40 plate 12 with the return tube of the fluid upward.

Tube plate 12 can be constructed as indicated by Fig. 5 as a single element, or else it can be composed of several parts.

Fig. 7 shows a free tube plate realized by means of two 45 metallic discoidal elements 20 disposed parallel with each other and spaced by a cylindrical element 21 to which they are welded.

Conduits B' have their ends connected to one of plates 20 while on the other plate removable caps 22 are provided for cleaning.

To the end of improving the strength of the tube plate, the latter is provided with one or more cylindrical through pins 23 welded at the outside to discoidal elements 20.

Inside of the tube plates realized in this manner, diaphragms can be disposed intended to determine the desired travel of the inner fluid.

Diaphragms of such a type are represented in Fig. 8.

In Fig. 9 the tube plate is of the demountable type, realized with two metal discoidal elements 25 provided with a projecting peripheral lip 26 playing the part of a distance piece and interconnected by a circle of bolts 27.

Between the two lips 26 a gasket 28 is provided.

Tubular elements B'' are anchored to one of the 65 plates 25.

Auxiliary tension bolts 29 increase the stability of the apparatus by acting in contrast with a co-axial tubular distance piece 30.

In this case the inspection and cleaning plugs are not 70 provided inasmuch as plate 25 to which tubes B'' are not connected can be removed as a whole from the other plate 25.

The exchanger according to Fig. 10 comprises a cylindrical outer envelope 31 with inlet and outlet connections 32 and 33 for the outer fluid, an upper tube plate 34 to which plate tubes 35 for the inner fluid are anchored, and a lower tube plate 36 made of two elements removably connected to each other in a way similar to Fig. 9. The arrival of the inner fluid takes place through center conduit 37 which is also connected to tube plates 34 and 36. From tube plate 36 the fluid ascends into conduits 35 and goes out through connection 38 of cover 39 with which cylindrical outer envelope 31 is provided.

The exchanger according to Fig. 11 comprises a cylindrical outer envelope 40 provided with outer fluid inlet and outlet connections 41 and 42, a tube plate 43 which is fixed and rigidly holds the ends of tubes 44 for the inner fluid. The other end of tubes 44 is fast to the free tube plate 45, which is of the demountable type and provided with an axial internal fluid outlet conduit 46. The inlet of the inner fluid takes place through bottom cover 47. Conduit 46 freely slides water-tight through the end of the outside envelope 40 so as to permit a free expansion of the tube bunch. The stuffing box 48 is so dimensioned as to permit during erection the passage through the envelope of the end flange of conduit 46. To permit the assembling of the stuffing box, its two parts are divided in a plane passing through the axis.

The exchanger according to Fig. 12 comprises a cylindrical outer envelope 50 provided with connections 51 and 52 for the inlet and outlet of the outer fluid, a tube bunch 53 connecting two tube plates 54 and 55, both free and demountable, each of them provided with an axial conduit 56 for the passage of the inner fluid. Conduits 56 are free to expand axially in respect to the envelope, and stuffing boxes 57 are provided. The inside surfaces of conduits 56 and tube plates 54 and 55 are coated with a corrosion resisting material, so that the mechanical strength to resist the internal pressure is trussed to the outer material, apt to withstand high stresses.

It is of course understood that the particulars of construction of the exchanger may vary without going, for this reason, out of the ambit and protection of the patent of invention. I claim:

1. A heat exchange apparatus, comprising, in combination, an elongated fluid-tight housing having opposite end walls and defining a chamber; a plurality of first and second tubular members in said chamber and extending in the direction of its length, each of said tubular members being connected in the region of one end thereof to one of said end walls and having an opposite end spaced from the other of said end walls; combined connecting and conduit means in said chamber, connecting said opposite ends of said tubular members and placing discrete assemblies of first tubular members in communication with discrete assemblies of second tubular members, each of said assemblies including a plurality of tubular members arranged in a row, the axes of the tubular members of an assembly of first tubular members and the axes of the tubular members of the corresponding assembly of sec-

ond tubular members lying in a common plane, said combined connecting and conduit means being independent of said housing and movable relative thereto in the direction of its length, said combined connecting and conduit means being constituted by an integral plate member arranged in said chamber normally to the direction of the length thereof, said plate member being formed with a plurality of substantially parallel bores therethrough, each adapted to receive in the region of one end thereof one of said tubular members and with a plurality of transverse passages between the outer faces of said element placing discrete assemblies of bores in communication with each other, each of said last-mentioned assemblies being constituted by bores adapted to receive a discrete assembly of first tubular members and the corresponding assembly of second tubular members, whereby a fluid medium introduced into said one end of any one of said first tubular members may flow therethrough, through said combined connecting conduit means, and through a second tubular member which is included in that assembly of second tubular members which is placed in communication by said combined conduit and connecting means with that assembly of first tubular members in which said one first tubular member is included while another fluid medium flows through said chamber exteriorly of said tubular members thereby permitting heat exchange to take place between the fluid media and whereby said combined connecting and conduit means may move relative to said housing in the direction of its length during lengthwise expansion and contraction of said tubular members; and a plurality of closure means in each of said bores, respectively, in the region of the opposite ends thereof, said closure means being removable from said bores so as to permit cleaning thereof and of said tubular members.

2. A heat exchange apparatus as defined in claim 1 wherein each of said plurality of transverse passages extends to the rim portion of said element; and a plurality of additional closure means in each of said passages, respectively, in the region of said rim portion, said additional closure means being removable from said passages so as to permit cleaning thereof.
